MOBILE LOUNGE CHAIR

Clarence E. Jackson, P.O. Box 1109,
Texas City, Tex. 77590

Filed Dec. 19, 1969, Ser. No. 20,577

Term of patent 14 years

Int. Cl. D6—01

U.S. Cl. D15—11

FIG. 1 is an isometric view showing a mobile lounge chair design; and

FIG. 2 is a rear view of such mobile lounge chair in elevation.

The side of the chair not shown is a mirror image of the side shown.

I claim:

The ornamental design for a mobile lounge chair, substantially as shown and described.
